UNITED STATES PATENT OFFICE.

MARION E. McMASTER, OF QUINCY, ILLINOIS.

PRINTING-INK.

No. 877,219.

Specification of Letters Patent.

Patented Jan. 21, 1908.

Application filed May 10, 1906. Serial No. 316,191.

To all whom it may concern:

Be it known that I, MARION E. McMASTER, a citizen of the United States, residing at Quincy, in the county of Adams and State 5 of Illinois, have invented a new and useful Printing-Ink, of which the following is a specification.

This invention relates to printing ink, and has for its principal object to provide a 10 printing ink which will not "print back", that is to say, an impression will not be formed by the engagement of a freshly printed sheet with another sheet with which it may engage.

15 A further object of the invention is to provide a printing ink which may be made at a comparatively small cost and employed to advantage on rapidly running presses.

With these and other objects in view, the 20 invention consists in the printing ink herein-after described and particularly pointed out in the appended claims.

In carrying out the invention, any ordinary printing ink is used as a basis, and with 25 this ink is mixed a quantity of milk, preferably skim milk, the ink being mixed directly with the milk or in some cases, especially where the ink is not to be used for a long period of time an antiseptic agent of any desired character, such as mercuric chlorid, may be previously mixed with the milk. The resulting 30 article will have the consistency of ordinary printers ink or a spissitude approximating that of coagulated blood.

35 In practice it is found that even quantities of printers ink in the condition in which the latter is found on the market, and milk will, when mixed together, form a brilliant lasting ink, the printing being more or less glossy as

the ink forms a slight skin which immediately 40 hardens or dries and from which no impression can be made, in other words, there is no printing back from sheet to sheet such as frequently happens in rapidly running presses. 45

While the mixture of manufactured ink with milk constitutes the most simple method of utilizing the invention, it is apparent that the milk may be combined with other ingredients during the manufacture of the 50 ink and mixed in any manner with the linseed oil, resin, pigment, and other ingredients which are employed.

Where the ink is to be stored for any considerable length of time before use it is preferred to add some antiseptic or preservative compound to the milk before the latter is mixed with the ink. 55

Having thus described the invention, what is claimed is:—

1. Printing ink having milk combined therewith and having a spissitude approximating that of coagulated blood. 60

2. Printing ink formed in part of skim milk and having a spissitude approximating 65 that of coagulated blood.

3. Printing ink formed in part of milk with which an antiseptic has been combined, the article having a spissitude approximating 70 that of coagulated blood.

In testimony that I claim the foregoing as my own, I have hereto affixed my signature in the presence of two witnesses.

MARION E. McMASTER.

Witnesses:

E. HUME TALBERT,
JNO. E. PARKER.
